UNITED STATES PATENT OFFICE.

GEORGE CHARLES CHADWICK, OF MELBOURNE, VICTORIA, AUSTRALIA.

UNLOADING APPARATUS.

1,422,926.

Specification of Letters Patent.

Patented July 18, 1922.

Application filed July 18, 1918. Serial No. 244,745.

To all whom it may concern:

Be it known that GEORGE CHARLES CHADWICK, a citizen of the Commonwealth of Australia, residing at "Ludstone Chambers," 5 352 Collins Street, Melbourne, in the State of Victoria, Commonwealth of Australia, has invented new and useful Improvements in Unloading Apparatus, of which the following is a specification.

10 This invention has been devised to provide improvements in apparatus to conveniently, efficiently and quickly discharge material such as coal, from the hold of a ship lying alongside a wharf or pier. By the 15 employment of the apparatus the coal is taken from its bed in any part of the hold, at any angle and delivered at any desired point. The whole apparatus may be operated by three men, one at an elevated station 20 surmounting an elevator well and having a master control, and the others at two other positions, each having an emergency control, whereby a portion of the apparatus may be arrested, if desired, at any moment.

25 Each of the lower positions may be in telephonic communication with the master control on the elevated station. When the apparatus is not in use, the elevator well and its adjuncts, carried by a gantry, will be 30 housed in an elevated position out of the way.

In order that my invention may be the more easily understood, reference will be made to the accompanying drawings, in 35 which—

Figure 1 illustrates apparatus embodied in my invention and shown in the position of unloading coal from a vessel.

Figure 2 is an enlargement of portions 40 of Figure 1.

Figure 3 is a perspective view of the chute and the non-rotating sleeve hereinafter referred to.

Figure 4 is a plan view of the adjustable 45 extension of the elevator well and of portions of the endless flexible elevator herein-after referred to, some of the parts being removed for sake of clearness.

Figure 5 is an end view of the tumbler 50 at the outer end of the extension and portions of the flexible elevator.

Figure 6 shows in perspective, the form of elevator bucket preferably employed.

Figure 7 illustrates one of the tumblers 55 under which the buckets pass in the extension, on the way to the elevator well.

Figure 8 is a plan view of the conveyor arm, the conveyor being omitted for sake of clearness.

Figure 9 is a fragmentary enlargement of 60 a portion of Figure 8.

Figure 10 is a side view of the conveyor arm, showing means for tightening or loosening the conveyor belt on said arm.

Figure 11 is a section on line 11—11 of 65 Figure 2.

Figure 12 is a top plan view, showing portions of the elevator well and portions of the stay rods.

Fig. 13 is a section on line 13—13 of 70 Figure 2.

Figure 14 is a fragmentary view, showing portions of the conveyor arm.

In the accompanying drawings, *a* is a double gantry travelling along rails *a'* upon a 75 wharf *a''*, the gantry being preferably provided with grooved wheels *a''*, two at each corner. The inner end of a movable hinged conveyor arm *b* is disposed within the gantry, such end being supported by a spindle *b'* 80 (Figure 9) carrying grooved wheels *b''* running on tracks *c*. Between the members of the arm *b* and integral with the spindle *b'* is a screw block *c'* (Figures 8 and 9), on which operates a screw rod *c''*, the latter receiving motion from a bevel gear *d* (Figure 8), operated in any convenient manner. The outer end of such conveyor arm *b* is pivoted at *b''* to a non-rotating vertical sleeve *e*, in which is disposed a rotary elevator well 90 *e'*, partly supported by wheels *e''* running on the top of the sleeve. The well *e'* is provided with a movable house *f* supported on a turn table *f'*. The rotary movements of the house are controlled by a motor *g* (Figure 95 2) operating a vertical rod *g'*, with gear wheel *g''* meshing with a circumferential gear wheel *g'''* on the exterior of the top of the rotary well *e'*. Preferably placed on the top of the house is a winch *h* with drum *h'*, 100 for two controlling ropes *h''* which pass down to and over the pulleys *i* and *i'* at each side of the rotary well. The ropes *h''* are finally connected to the pulley wheel *i''* (Figure 2) of the adjustable arm or extension *j*, which is pivotally suspended at the bottom of the rotary well, *e'*. Mounted at the outer end of the adjustable extension *j* is a tumbler *j'* (Figure 5), providing with projecting agitators *j''* which, in the rotary 110 action of the tumbler, stir the coal within the vessel *j'''*, to facilitate its entry into the

buckets k . The latter are pivotally connected to links k' of endless chains which slide on transverse rollers k^2 (Figure 4), running in bearings on the side members of the extension j , said buckets and chains constituting elements of an endless flexible elevator. The buckets pass from the extension j under the tumblers m , journaled in the lower end portion of the well, and then proceed vertically through the well e' to and over a tumbler n' , journaled in a structure or house f above the well, and rotated by a drum h^3 on a motor-driven shaft h^4 , and belted to the shaft of the tumbler n' .

15 Within the house f the coal at this point is discharged into an annular hopper n (Figures 2 and 3), the buckets in the meantime passing over a tumbler n^2 , below the tumbler n' , thence down the well e' , and 20 over the tumbler n^3 at the lower end of the well, and thence into the adjustable extension j .

The hopper n is fixed to and surrounds the upper end of the sleeve c , and is formed to 25 receive coal delivered by the elevator when the latter is in any position to which it may be rotated. From the lower portion of one side of the hopper projects an inclined chute n^4 , arranged to deliver coal to the conveyor belt hereinafter described. The coal on falling into the hopper will strike any of the four inclined director plates o set at an angle within the hopper to cause the coal to 30 continue to fall towards the mouth of the chute n^4 , from which it again falls onto a conveyor belt o' running on the usual rollers o^2 set at an angle on the conveyor arm b , to provide the ordinary V-shaped receptacle or channel. The belt o' is retained in its taut 35 condition by passing it over a number of small pulleys p (Figure 10), and also extended by employing an adjustable arm p' , on which is mounted one of the main pulleys p^2 . The arm receives its forward or 40 rearward movement from a screw-rod p^3 , rotated in any convenient manner. It is necessary that the inner pulley of the pulley p^2 should be drawn inwardly, otherwise the belt o' will strike the bin s hereinafter referred to, when the arm b is being housed.

To keep the elevator well in a vertical and staunch position against the thrust caused by the pressure on the adjustable extension j , when the elevator is at work, I provide inclined stay-rods r , (Figures 1, 8, 12 and 13), the outer or lower ends of said rods being pivotally connected to a non-rotating ring u encircling the well e' , such ring u having suitably arranged anti-friction rollers u' in 55 contact with a circular plate u^2 on the elevator well, and with flanges on said plate, as shown by Figures 11, 12 and 13. The upper ends of the rods r are supported by spindles r' (Figure 8) integral with a screw block r^2 running on a screw-rod r^3 disposed

within the arm b . The rod r^3 is operated by the movement of the pulleys t' , the hauling ropes t actuating such pulleys t' and the pulleys t^2 on the spindle t^3 . A driving-belt or the like t^4 connects the pulley t^2 with pulley t^5 mounted on worm shaft t^6 gearing with worm screw t^7 on the screw-rod r^3 . The spindles r' carry grooved wheels r^4 running on tracks r^5 (Figure 8) at each side of the screw-rod r^3 . The coal is deposited by the 75 conveyor belt into a suitable bin s (Figure 1) from which it falls into a receptacle s' , thence into a chute s^2 which delivers it onto a conveyor belt s^3 that finally takes it to a storage bin, not shown, or to any other required point. The raising or lowering movement of the conveyor arm b , and with it the elevator, are controlled by a rope t passing over pulleys t' at each side of the conveyor arm and pulleys v at the top of the gantry, the rope passing downwardly and being wound around a drum v' disposed within the gantry, at any convenient position, and operated in any suitable manner. When the rope t is operated to raise 80 the elevator well, the screw-rod r^3 is rotated by the rope to move the screw block r^2 and spindles r' inwardly from the elevator and thus vary the inclination of the rods r to compensate for vertical movements of the 85 well.

I would have it understood that I may deposit the coal into any suitable receptacle, for instance, it may be deposited simultaneously into one or more lines of trucks. 100 The operating power preferably employed is electricity for traversing the gantry along the wharf, for driving the drums for raising or lowering the conveyor arm, for driving the conveyor belt on said arm, for driving the flexible elevator, for turning the well to cause lateral swinging movements of the hinged extension j , and for swinging said extension vertically.

In unloading the vessel j^3 , the height of 110 the elevator well e' , and the position of the hinged extension j are adjusted to cause the elevator buckets to first engage the top portion of the cargo. The well is lowered and turned in the sleeve c , and the extension is 115 swung in a vertical plane, as required, to enable the buckets at the outer end of the extension to reach different parts of the cargo. The stay-rods r act as compression members or struts, supporting the well and 120 extension against the pressure exerted on the buckets by the coal when the extension is inclined to the right, as shown by Figures 1 and 2. When the extension is inclined in the opposite direction, the stay-rods act as 125 tension members to similarly support the well and extension. Provision is therefore made for supporting the well, elevator, and extension at all times against the pressure exerted on the buckets by the coal, and 130

maintaining the well in a staunch vertical position.

I claim:

1. Unloading apparatus for vessels, comprising, in combination, a gantry; a conveyor arm hinged thereto at its inner end, and adapted to swing in a vertical plane; a non-rotating sleeve hinged to the outer end of said arm; a rotary elevator well rotatable in said sleeve portion; an adjustable extension hinged to the lower end of the rotary well; a flexible endless elevator guided by said well and extension, and including elevating buckets, adapted to take up material at the outer end of the extension; means for swinging the conveyor arm to raise and lower the sleeve and well; means for swinging the extension to vary the height of its outer end; inclined thrust-supporting stay-rods; upper hinge connections between the upper ends of said stay-rods and the conveyor arm; lower hinge connections between the lower ends of the stay-rods and the rotary well, said lower connections including a non-rotating ring pivoted to the lower ends of the stay-rods and encircling the rotary portion of the well, said stay-rods being arranged to maintain the well in a vertical and staunch position against the thrust caused by the pressure of the material on said buckets; and means for turning the rotary well to swing said extension laterally.
2. Unloading apparatus, comprising a conveyor arm; conveying means on said arm; a non-rotating sleeve connected with

said arm; a rotary elevator well adapted to turn in said sleeve portion; means for elevating material in said well and discharging the same over the upper end of the sleeve; and an annular hopper fixed to and surrounding said sleeve, and provided with a chute, projecting from one side of the hopper, and arranged to guide material from any part of the hopper to the said conveying means.

3. Unloading apparatus substantially as specified by claim 2, said hopper being provided with oppositely inclined director plates between its mouth and the chute, arranged to guide the material toward the mouth of the chute.

4. Unloading apparatus, comprising a non-rotary sleeve; a rotary elevator well adapted to turn in said sleeve; anti-friction means associated with the sleeve and the rotary well, whereby the well is supported by the sleeve and permitted to rotate; means for supporting the sleeve; an extension hinged to the lower end of the rotary well; an endless flexible elevator movable in said well and extension, and including elevating buckets and endless chains carrying the buckets; means for guiding said elevator, including a rotary tumbler located above the well; mechanism for driving said tumbler; mechanism for turning the rotary well, and mechanism for vertically swinging said extension.

In testimony whereof I have signed my name to this specification.

GEORGE CHARLES CHADWICK.
